DISPLAY DISPENSER FOR CONTINUOUS STRIP MATERIALS

Melvin E. Levy, Los Angeles, Calif.

Application October 1, 1956, Serial No. 43,151

Term of patent 14 years

(Cl. D52—2)

Figure 1 is a perspective view of a display dispenser for continuous strip materials, embodying my new design; for continuous strip materials, substantially as shown and described.

Figure 2 is a side elevational view thereof;

Figure 3 is a right end elevational view thereof; and

Figure 4 is a top view thereof.

The undisclosed side and end of the display dispenser are substantially the same in appearance as the side and end shown in the drawing.

I claim:

The ornamental design for a display dispenser for continuous strip materials, substantially as shown and described.
